(57) **CLAIM**

The ornamental design for planar antenna, as shown and described.

DESCRIPTION

FIG. 1 is a perspective view of a planar antenna showing the claimed design;

FIG. 2 is a top view thereof;

FIG. 3 is a bottom view thereof;

FIG. 4 is a right side view thereof; and,

FIG. 5 is a left side view thereof.

The broken lines illustrate environment and portions of the antenna that form no part of the claimed design.
